METHOD OF AND APPARATUS FOR
MAKING CASTSClifford K. MacDonald, Brockton, Mass., assignor
to United Shoe Machinery Corporation, Pater-
son, N. J., a corporation of New Jersey

Application May 25, 1933, Serial No. 672,861

29 Claims. (Cl. 18—5)

This invention relates to methods of making casts and other replicas and to apparatus for use in making such objects and is herein illustrated with reference to the production of plaster casts of human feet.

When making a cast of a particular article it is necessary first to procure a mold or matrix which will correspond exactly in shape to the article which is to be reproduced. This may be done by placing the article in plastic material such, for example, as plaster of Paris or wax in liquid form, and holding the article stationary in the plastic material while the latter sets. After the plastic material has hardened, the article is removed thereby leaving an impression in the mold which corresponds in shape to the outer surface of the article.

It will be seen that considerable time is lost in making molds in the manner described above because the article must remain in the plastic material until the latter has completely hardened. Moreover, if the mold is, for example, of wax and is to be used only once or twice for a special purpose and thereafter reduced to a plastic condition and used in making a different shaped mold, additional time is lost while the material is being melted or otherwise brought into a plastic condition before it can be used again.

When a mold is to be made from an animate object such as a human foot another difficulty arises. Unless the foot is held perfectly stationary while the plastic material is setting, the resulting impression will not correspond exactly in shape to the outside surface of the foot. It is extremely difficult for a person to hold his foot perfectly still during the time it takes for the available plastic material to set, unless the foot is resting on a support, which, of course, will prevent a perfect impression from being obtained. Moreover, the heat of many plastic materials in melted form, even when not so great as to be prohibitive, makes it even more difficult to secure good results. A further objection to this method of making casts arises from the fact that it is practically impossible to secure an impression of a foot while the latter is supporting the weight of the body because, obviously, the plastic material itself affords no support upon which the person can bear his weight and, as stated, if a support for the foot is used, the resulting impression will not be perfect at those portions of the foot which engage the support.

Objects of the present invention are to provide an improved method of making casts or other replicas whereby difficulties such as those pointed

out above will be eliminated, and to provide also an improved apparatus for carrying out this method.

The illustrated method in one aspect consists in reproducing an article by making an impression of the article in magnetizable granulated material which is in a mobile condition and, while the article is still resting in the material, rendering the latter immobile by magnetization so that the article may be removed and the impression used for making a plaster cast of the article. As illustrated, the mobile granulated material comprises a mass of small particles, preferably balls of magnetizable material, for example iron or steel, which rest loosely on a support in a container and which are readily displaceable by pressure so that they may be molded to the shape of an article pressed against them. The mass of magnetizable particles or balls is rendered immobile by means of a magnet, preferably an electro-magnet, which causes a magnetic field to pass through the space occupied by the balls and causes the latter to become rigid and to remain rigid as long as the magnetic field is maintained. An impression thus formed in the mass of magnetizable balls can be used at once as a mold from which to make a plaster cast of the article which was used in making the impression, thereby saving the time which it would ordinarily take for a mold composed of plastic material such as wax or plaster of Paris to harden.

In making a cast of a foot by the method of the present invention, the foot is pressed against the magnetizable particles or balls until it sinks to the desired depth and a magnetic field is then set up in the space occupied by the balls to cause them to become locked rigidly in position, thereby retaining the impression formed therein so that the foot may be removed at once without injuring the impression. Since the balls afford a support for the foot, the entire weight of the body may be placed thereon if it is desired to obtain an impression of the foot while the latter is supporting the weight of the body.

The illustrated apparatus which constitutes a preferred embodiment of the invention in its apparatus aspect, and which may be used as an aid to the practice of my new method, is provided with a hollow frame or container, means for supporting a mass of magnetizable particles or balls within the container, and means for setting up a magnetic field in the space occupied by the magnetizable material. The supporting means is illustrated as composed of a non-magnetizable substance and is adjustable so that the upper

surface thereof can be made to conform more closely to the bottom surface of the foot. A magnetic field is set up by a magnet, preferably an electro-magnet, which magnetizes certain 5 magnetizable portions of the container and causes the magnetic flux to extend into such portions and set up a magnetic field between them. In order to control the mobility of the mass of balls, means such as a rheostat is preferably provided 10 for varying the strength of the current sent through the coils of the magnet.

With the above and other objects in view, the invention will now be described with reference to the accompanying drawings and pointed out 15 in the appended claims.

In the drawings,

Fig. 1 is a side elevation of the apparatus embodying the present invention with a foot mounted therein, the frame or container being shown in 20 section and the magnet being illustrated with its central portion broken out;

Fig. 2 is a plan view of the apparatus shown in Fig. 1 with the support broken away to illustrate details, the foot being shown in broken lines;

Fig. 3 is a cross-sectional view of the apparatus taken on the line III—III of Fig. 1;

Fig. 4 is a view similar to Fig. 1 after an impression of the foot has been made in the iron balls, the impression lined and filled with plastic material, and a "spirit" level placed in the plastic material at the heel end of the impression;

Fig. 5 is a view similar to Fig. 4 after the cast of the foot has been removed from the balls and the current of the magnet has been turned off; 35 and

Fig. 6 is a perspective view of the finished cast.

The apparatus and method disclosed herein for producing casts are adapted for use in the manufacture of orthopedic shoes and are illustrated herein with reference to the production of 40 casts of feet for which orthopedic shoes are to be made. It is to be understood, however, that in many of its aspects the invention is not limited to the production of casts of feet for orthopedic 45 shoe work but may be employed to advantage in many other instances where exact reproductions of particular articles are required.

The illustrated apparatus comprises an elongated rectangular frame or container 10 which is 50 preferably about 8 or 10 inches high and is open at the top and bottom. The container has an inside area which is large enough to permit an adult person's foot to be conveniently located therein and still leave considerable space around 55 the foot. The vertical side walls 12, 14 of the container, as illustrated herein, are formed of relatively thick plates of iron or steel, the outer surfaces of which taper inwardly at the upper portion of the apparatus so that the top surfaces 60 of the side walls will be only about half as wide as their lower surfaces. The inner portions of these lower surfaces project downwardly a short distance to form lugs or shoulders which extend lengthwise of the side walls and form means 65 whereby the container may be positioned on the upper side of a large magnet 20, illustrated herein as an electro-magnet. The ends of the rectangular container are formed by a pair of thin plates 16 and 18, preferably of brass or some other 70 relatively non-magnetizable material, which are secured to the side plates 12 and 14 by means of screws 19.

The electro-magnet 20 upon which the container rests is a horse-shoe- or U-shaped magnet 75

having soft iron cores 22 and 24 connected by a horizontal yoke piece 26, the cores being secured to the yoke piece by means of screws 28. The cores 22 and 24 are wound respectively with magnetizing coils 30, 32 of insulated wire through 5 which a current is passed around the cores to magnetize the latter and set up a magnetic field having lines of force extending between the cores. The upper ends of the cores 22, 24 have projections or shoulders formed thereon which 10 are located outside the downwardly projecting shoulders on the side walls or plates 12 and 14, thereby forming a guideway in which the container 10 can be conveniently located centrally of the electro-magnet. As shown in Fig. 1, the cores 15 22 and 24, which form the poles of the magnet, and the yoke piece 26 are equal in length to the rectangular container and the cores are substantially uniform in cross section. When the container 10 is mounted on the electro-magnet, the 20 side walls 12 and 14 form extensions of the poles 22, 24 so that the magnetic flux of the magnet will extend into the side walls and produce a relatively strong magnetic field between such walls. In order that the magnetic field between the side 25 walls 12 and 14 will be sufficiently strong, those parts of the apparatus which are located between the walls, and which would have a tendency to reduce the strength or density of the field if they were composed of magnetizable materials, are 30 made of relatively non-magnetizable materials such as brass or aluminum, as will hereinafter appear, so that the magnetic field will be concentrated as much as possible between the side walls 12 and 14. 35

Instead of making the container 10 as a separate unit to be mounted on the electro-magnet 20 in the manner described, the soft iron cores 22 and 24 which form the poles of the electro-magnet may, if desired, be extended upwardly beyond the magnetizing coils 30, 32 to form the side walls of the container, the end walls of the container being secured to these cores in the manner set forth above. With this construction, in which the cores of the electro-magnet also form the 45 side walls of the container, there will, of course, be no joints or breaks in the opposite poles of the electro-magnet.

The magnetizing coils 30, 32 of the electro-magnet are wound in series and a rheostat 34 is 50 provided for varying and controlling the strength of the current passed through the coils. The rheostat is indicated diagrammatically in the drawings and is adapted to turn the current on and off, or to permit only a limited amount of 55 current to pass through the coils so that the strength of the magnetic field can be increased or reduced as desired. The electro-magnet 20 and the container 10 mounted thereon form a complete unit which may be mounted, for example, on a base 31 and moved about on wheels or casters, or it may, if desired, be incorporated in orthopedic apparatus, such as an orthopedic chair of the type disclosed in Letters Patent of the United States No. 1,981,941, granted November 27, 1934, on an application filed in the name of William L. Baxter. As herein disclosed the apparatus is illustrated as a single unit projecting through an opening in a horizontal table 33 of any ordinary type such, for example, as the supporting table or platform shown in the Baxter patent referred to. Since the table forms no part of the present invention it has not been shown in detail.

Mounted inside the rectangular container or 75

frame 10 is a supporting member 35 (Fig. 1) of aluminum or an aluminum alloy, the member 35 being made up of several sections which are pivotally connected together so that they can be 5 adjusted to different positions heightwise of the container. A forward or toe supporting section 36 of the supporting member 35 is fixedly secured by screws 38 and 40 to the side walls of the container, the screws passing through downwardly 10 projecting flanges on the section 36 which contact with the inner surfaces of the side walls 12 and 14 so that the upper surface of the section will occupy the full space widthwise of the container. The forward end of the section 36 abuts 15 against the brass plate 16 so that no space is left between the section 36 and the container at the front end thereof. A middle or shank supporting section 42 of the supporting member 35, having its forward end engaging the rear end of the 20 fixed section 36, is pivotally mounted in the side walls 12 and 14 by means of a pair of cylindrical lugs or trunnions 44, 46 which are formed at each side of the forward end of the section 42 and extend into circular openings formed in the 25 inner portions of the side walls. As shown in Fig. 1, this middle section 42 normally extends rearwardly or toward the heel end of the container on an upward incline, thereby causing the central or intermediate portion of the supporting 30 member 35 to conform more closely to the longitudinal curvature of the shank portion of a foot.

Projecting downwardly from the forward end of the inclined middle section 42 is a pair of ears 48 and pivotally connected to these ears by means 35 of a pin 50 is a horizontal link 52, which extends rearwardly and is pivotally connected by a bolt 53 to another pair of ears 54 projecting downwardly from the lower side of an upwardly extending supporting arm 56. The arm 56 is pivotally mounted in circular recesses formed in the opposite side walls of the container 10 by means 40 of cylindrical lugs or trunnions 58 and 60 which project horizontally from opposite sides of the arm. The upper end of the arm 56 is pivotally secured to a pair of downwardly projecting lugs 61 formed on the under side of a third section 62 of the supporting member 35, the section 62 being pivotally connected at its forward end to the middle section 42 by short horizontal pins 64, 66 45 fastened to the third section by set screws and extending through circular openings in a pair of small rectangular plates which are retained in lugs in the middle section 42 by two pairs of pins, indicated by the numerals 68 and 70. This arrangement insures that there will be no open 50 space left at the point where the upper surface of the section 62 of the supporting member 35 joins the upper surface of the section 42. The rear end of the section 62 terminates a short distance 55 inside the brass end plate 18 and has an upwardly projecting portion 72 formed thereon which provides a vertical back or end plate for the sectional supporting member 35. The middle section 42 and the rear section 62 are both substantially as wide as the space between the inner 60 surfaces of the side walls of the container will permit, having only the clearance necessary to permit adjustment of these sections.

The rear or heel end supporting section 62 is 65 located in a substantially horizontal position, as shown in Fig. 1, and may be adjusted heightwise of the container while supported in this position. To effect such adjustment there is provided a horizontal shaft 74 which extends through the 70 lower portion of the container 10 and at its inner

end is threaded into a large lug 76 formed on the forward end of the bolt 53 which connects the horizontal link 52 to the downwardly projecting ears 54 on the supporting arm 56. The middle portion of the shaft 74 is supported in the container by means of a horizontal bracket 78 which is pivotally mounted between the side walls 12 and 14 by means of a pair of cylindrical lugs or trunnions 80, 82 which extend into horizontal recesses formed in the side walls. In order to 10 prevent the shaft 74 from moving lengthwise of the container, a pair of collars 84, 86 are pinned to the shaft at either side of the supporting bracket 78, as shown in Fig. 2.

The forward end of the shaft 74 extends 15 through an opening in the brass end plate 16 and has fixedly mounted thereon a hand wheel 88 by which the shaft may be rotated in its bearings in the bracket 78. By rotating the shaft 74 the lug 76 will be moved along the threaded portion of 20 the shaft to swing the supporting arm 56 about its pivots 58, 60, thereby causing the rear end of the section 62 to be raised or lowered as the case may be. When the arm 56 is rotated the horizontal link 52, which extends between this arm 25 and the ears 48 of the middle section 42, will cause the section 42 to be rotated about its pivots 44, 46 and to move an amount equal to the movement of the supporting arm 56. In this way the section 62 is always maintained in a horizontal 30 position regardless of the height to which it is adjusted, and the middle section 42, which pivots about its forward end, will be inclined at different angles depending upon the heightwise position of the horizontal section 62. The above arrangement permits the supporting member 35 to be adjusted until its upper surface assumes a shape which will conform substantially to the longitudinal curvature or contour of the bottom surface 35 of the foot being operated upon regardless of the 40 shape of such foot.

The aluminum supporting member 35 is adapted to support a mass of mobile magnetizable material which is illustrated herein as a relatively thick layer of small iron or steel balls 90 piled 45 loosely on the upper surface of the supporting member. As shown in Figs. 1 and 3, the balls 90 cover the upper surface of the supporting member with a layer of mobile material which is from about 1½ to 2 inches thick. Since the balls rest 50 loosely on the member 35 and are not more than $\frac{1}{16}$ of an inch in diameter, they may be readily pressed into different positions when an object, for example, a human foot is pressed forcibly 55 against them. This loose, mobile condition of the mass of balls permits them to be pressed closely against the surfaces of an object forced against them so that an impression formed in the mass of balls will correspond accurately to the shape of the object.

In the use of the illustrated apparatus, which may be referred to as a magnetic box, an article to be reproduced, for example, a human foot 92, is placed in the container against the mobile mass of iron balls 90. In making a cast of a 65 foot the proper adjustments should, of course, be made in the sectional support 35 by means of the hand wheel 88 to accommodate the support to the longitudinal contour of the foot or, in other words, to position the support in accordance with 70 the toe spring and heel height of the foot as determined by the foot itself or as indicated, for example, by a shoe appropriate for such foot. The current of the electro-magnet 20 is then turned partly on, as indicated at 75 75 in Fig. 1, to

set up a magnetic field between the side walls 12 and 14 which will have lines of force passing through the space occupied by the mass of balls 90. This magnetic field will magnetize the iron balls to an extent sufficient to cause them to adhere somewhat to each other but still to be displaceable under pressure. The person then bears his weight up on his foot which causes the foot to sink further into the balls until the foot is embedded up to about the tops of the toes. The current of the electro-magnet is then turned on full, as indicated in Fig. 4, to cause the density of the magnetic field between the side walls 12 and 14 to become greatly increased, thereby magnetizing the balls to such an extent that they become a substantially rigid mass which cannot be displaced by further pressure as long as the current remains on. The foot is then withdrawn from the mass of balls to leave an impression 93 therein which corresponds exactly to the shape of the foot 92 and which is permanent as long as the magnetic field is maintained.

A thin sheet 94 of limp stretchable material such as rubber is now laid in the impression 93, thereby lining the impression and covering the small openings between the balls. Plastic material 95, such as plaster of Paris in a liquid or semi-liquid condition, is poured into the impression to cover the rubber lining sheet 94 and to fill the impression substantially to the top. During this step of the method the current of the electro-magnet 20 remains fully on to maintain the field at its maximum density so that the balls will not become displaced and the impression damaged or destroyed. The plastic material 95 is now allowed to set until it is in semi-solid condition at which time a small circular level 96, commonly referred to as a "spirit level", is pressed into the semi-solid material at about the center 40 of the heel end of the impression. The level is moved about until it indicates that its lower surface is exactly horizontal and the plastic material is then allowed to harden to form the completed cast 93 (Fig. 5).

45 After the cast has hardened the current is turned off by moving the rheostat 34 around to the closed position indicated in Fig. 5, thereby destroying the magnetic field and permitting the balls to become loose and readily movable again. The cast is then lifted out of the balls with the rubber sheet 94 adhering lightly to its bottom surface and the mass of balls is smoothed out by hand to obliterate the impression 93 before the apparatus is used again. The rubber sheet 94 is stripped from the bottom of the plaster cast and the "spirit level" is removed and the cast is now ready for whatever use it is to be put, for example, for use in the manufacture of orthopedic shoes. Fig. 6 shows the completed cast 93 after the rubber sheet and the "spirit level" have been removed. A circular impression 100 formed by the "spirit level" will be seen at the heel end of the cast, the bottom surface of this impression forming means whereby the cast can be easily located in exactly the same position which it occupied in the original mold by placing a level in the impression 100 and moving the cast about until the level indicates that the bottom surface of the impression is exactly horizontal. This 70 facilitates the use of the cast in obtaining measurements for use in the manufacture of orthopedic shoes since all measurements taken from the cast will not only be accurate measurements of the foot from which the cast was made but will also be measurements of the foot when it is lo-

cated in a natural position and is upporting the weight of the body, the latter condition being essential in orthopedic shoe work.

Having thus described the invention what I claim as new and desire to secure by Letters Patent of the United States is:

1. Apparatus comprising a container, mobile magnetizable material carried thereby and adapted to receive an impression of an article to be reproduced, and a magnet for rendering said material immobile to retain the impression formed therein. 10

2. An apparatus for reproducing articles comprising a container having magnetizable walls, magnetizable material in the container, said material being readily displaceable to receive an impression of an article to be reproduced, and a magnet for setting up a magnetic field between the walls of the container and thereby rendering said material indisplaceable to hold said impression. 20

3. An apparatus for reproducing articles comprising a container, magnetizable granulated material carried by the container, said material being mobile to form an impression of an article 25 pressed therein, and an electro-magnet for rendering said material rigid to hold the impression.

4. An apparatus for reproducing articles comprising a container, a mass of loose spherical particles of magnetizable material carried by 30 said container, said particles forming a support and a molding medium in which an impression of an article may be made by pressing the article into said particles and maintaining the pressure, and an electro-magnet for 35 magnetizing the particles while the article is being pressed therein, thereby holding the particles rigid to retain the impression after the article is removed therefrom.

5. An apparatus for reproducing articles comprising a container, a mass of small iron balls carried thereby, said balls being arranged loosely in the container so that they are relatively movable and may be molded to conform closely to the shape of an article pressed against 45 them, and an electro-magnet for magnetizing the balls and causing them to become rigid so that an impression formed therein will be retained after the article has been removed. 40

6. An apparatus of the class described having, in combination, a container having opposite side walls of magnetizable material, a support in said container of non-magnetizable material, a magnet the ends of the opposite poles of which engage the side walls of the container, 55 thereby causing the magnetic flux to be extended beyond said poles and into said side walls, and a mass of loose particles of magnetizable material resting on the support and engaging said side walls thereby closing the magnetic circuit. 60

7. An apparatus of the class described having, in combination, a rectangular container open at the top and bottom and having its opposite side walls formed of magnetizable material, a support in the container for holding an object, a 65 magnet having opposite poles arranged to engage said side walls, thereby forming extensions of said poles and causing the magnetic flux to be extended into said side walls, and a mass of small magnetizable particles resting on said support and engaging said side walls thereby forming 70 a closed magnetic circuit through the container.

8. An apparatus for making casts of articles comprising a rectangular frame having side walls of magnetizable material, a non-magnetizable 75

support mounted in said frame, magnetizable material carried by said support, said material being originally in a mobile condition so that an impression of an article may be formed there-
 5 in by pressing the article into said material, and an electro-magnet engaging said side walls and extending the field of the magnet into the space occupied by said magnetizable material, thereby magnetizing said material and causing
 10 it to become rigid, so that the impression will be retained when the article is removed, thus permitting the impression to be utilized for producing a cast of the article.

9. An apparatus for making casts of articles comprising a hollow rectangular frame having relatively thick side walls of iron and thin end walls of brass, an aluminum support mounted in said frame, a plurality of small iron balls on said support, said balls forming a mobile mass
 15 of magnetic material that can be readily molded by pressure into various shapes, and an electro-magnet constructed and arranged to engage the iron walls of the frame and to set up a magnetic field which will be of greatest density in
 20 the space occupied by the balls, thereby magnetizing said balls sufficiently to cause them to become rigidly fixed in whatever positions they have been molded.

10. In an apparatus for making cast repro-
 25 ductions of objects, a container, mobile magnetizable material in the container and adapted to form an impression of a foot pressed therein under the weight of the body, means for balancing the foot in the position it is to assume in a shoe, and a magnet for rendering said mobile material immobile to retain the impression formed therein.

11. In an apparatus for making cast repro-
 30 ductions of objects, a container, an adjustable support in the container, mobile magnetizable material resting on the support and adapted to form an impression of a foot which is supporting the weight of the body, means for adjusting the support to balance the foot in accordance
 35 with the position it will assume in a shoe appropriate for said foot, and an electro-magnet for magnetizing said mobile material and rendering it rigid to hold the impression formed therein.

12. That improvement in methods of making casts of the extremities of human limbs which consists in placing the extremity of a limb in a mass of loose magnetizable particles which conform readily to the shape of said extremity, thereby producing an impression, magnetizing said particles to lock them in position and thus retain the impression, removing the extremity of the limb from the impression while the particles are still locked in position by magnetization, and utilizing the impression to form a cast of said extremity without demagnetizing the particles.

13. That improvement in methods of making casts of feet which consists in providing a support the supporting surface of which conforms to the longitudinal contour of a foot in the position it assumes in a shoe, said support having mobile magnetizable material thereon, pressing the foot into said material under the weight of the body, thereby forming an impression of the foot in the position it assumes in a shoe, rendering said material rigid by magnetization to hold the impression, removing the foot from the impression without demagnetizing the material, and using the impression as a mold to produce a cast of the foot while the material is still held rigid by magnetization.

14. An apparatus for producing a cast of a foot comprising a rectangular container having two opposite sides of magnetizable material and its other two sides of non-magnetizable material, means in the container for supporting a foot, said means being adjustable heightwise of the container to accommodate different shaped feet, means for adjusting the supporting means, magnetizable smooth-sided particles resting loosely on said supporting means and capable of forming an impression of the foot when displaced thereby, and an electromagnet for engaging the magnetizable sides of the container with its opposite magnetic poles and thereby extending the field of the magnet undiminished in strength into the space occupied by the magnetizable particles to render said particles immovable after an impression of the foot has been made therein.

15. An apparatus for producing a cast of a foot comprising an elongated metal container having side walls of iron and end walls of brass, an adjustable support mounted in said container, said support being made up of several sections so that the upper surface thereof can be made to conform substantially to the longitudinal contour of the bottom surface of a foot, means for adjusting said support, a mass of small iron particles mounted on the support, said particles being arranged loosely thereon to provide a mobile substance in which an impression of the foot may be made by pressing it against said particles, an electro-magnet for controlling the mobility of the mass of iron particles, said electro-magnet engaging the side walls of the container and creating a magnetic field in the space occupied by the particles which magnetizes the particles when a current is passed through the electro-magnet, and means for controlling the current to vary the strength of the electro-magnet.

16. An apparatus for producing a cast of a foot comprising a hollow oblong container having side walls of iron and end walls of brass, a support mounted in said container, said support being made of aluminum and being arranged in relatively adjustable sections so that its upper surface can be made to conform substantially to the longitudinal contour of the bottom of the foot operated upon, single means for adjusting the sections of the support relatively to each other, a mass of small iron balls resting loosely on said support, said balls serving as a support for the foot and as a molding medium in which an impression of the foot can be made by pressing the foot against the balls and maintaining such pressure, an electro-magnet for engaging the side walls only of the container and setting up a magnetic field between said walls when a current is passed through the magnet, thereby magnetizing the balls and holding them rigidly in position so that the foot may be removed therefrom to leave an impression in the balls which may be used to produce a plaster cast of the foot, and a rheostat for varying the strength of the electro-magnet so that the mobility of the mass of balls may be controlled by an operator.

17. That improvement in methods of reproducing articles which consists in making an impression of an article in magnetizable material which is in a mobile condition, rendering the material immobile by magnetization while the article is still resting therein, removing the article from the magnetized material, and using the impression thus formed as a mold from which to produce a cast of the article.

18. That improvement in methods of reproducing articles which consists in making an impression of an article in magnetizable granulated material which is originally in a mobile condition, magnetizing said material after the impression is made so that the material will become rigid and thus permit removal of the article without disturbing the impression, and utilizing the impression as a mold from which to make a plaster cast 5 of the article.
19. That improvement in methods of reproducing articles which consists in making an impression of an article in a mass of magnetizable smooth-surfaced particles which are originally in a mobile condition by pressing the article into said particles, creating a magnetic field in the space occupied by the magnetizable particles to cause the mass to become rigid so that the article may be removed therefrom without injuring the impression, and utilizing the impression thus formed to produce a cast of the article as soon as the latter is removed.
20. That improvement in methods of making casts which consists in making an impression of a yieldable object in mobile material consisting of a mass of loose magnetizable particles, rendering the mass of particles immobile by magnetization, thereby maintaining the impression formed therein, and using the impression as a temporary mold to produce a cast of said object.
21. That improvement in methods of making replicas of articles which consists in making an impression of an article in a mobile mass of magnetizable balls, said balls being small enough in diameter to form an accurate impression, magnetizing said balls and thereby transforming the mobile mass into a rigid mass to retain said impression, and using the impression thus formed as a mold with which to produce a replica of the article.
22. That improvement in methods of making casts which consists in obtaining an impression of an article by pressing it into a mobile mass of small iron balls, magnetizing said balls to transform the mobile mass into a rigid mass and thereby retain said impression, lining the impression with a thin sheet of stretchable material, filling the lined impression with plastic material, and permitting the plastic material to set while the balls are still magnetized, thereby producing a cast of the article.
23. That improvement in methods of making casts of feet which consists in pressing a foot into mobile material comprising a mass of small iron balls, magnetizing the balls to cause them to adhere closely to each other and thus to form a rigid mass, removing the foot from the balls and thereby leaving an impression of the foot formed therein, said impression being held intact by the magnetized condition of the balls, lining the impression with a thin sheet of limp stretchable material, pouring plastic material in a liquid form into the lined impression, allowing the plastic material to harden while the balls are maintained in a magnetized condition, thereby producing a cast of the foot, and demagnetizing the mass of balls to render them again mobile and thus to permit the ready removal of the finished cast.
24. That improvement in methods of making casts of feet which consists in adjusting a sec-
- tional supporting plate until its upper surface conforms substantially to the longitudinal contour of the bottom surface of a particular foot, said plate being mounted within a container and having magnetizable mobile material resting thereon, placing the foot in the mobile material and bearing the weight of the body thereon until an impression of the foot is formed in said mobile material, magnetizing said material with an electromagnet to render the material immobile so that the impression will be preserved when the foot is removed therefrom, removing the foot and lining the impression with a thin sheet of limp stretchable material, pouring plastic material in liquid form into the lined impression, and allowing the plastic material to harden while maintaining the field of the electromagnet at full strength, thereby producing a plaster cast of the foot.
25. That improvement in methods of reproducing articles which comprises creating a relatively weak magnetic field in the space occupied by a mass of small iron balls resting loosely on a supporting plate and being readily displaceable by pressure while adhering closely together in the absence of such pressure, pressing an article to be reproduced into the mass of iron balls to form an impression of the article therein, increasing the strength of the magnetic field to a degree sufficient to render the mass of balls indisplaceable, thereby causing the impression to become temporarily fixed so that the article can be removed without damaging said impression, utilizing the impression thus formed to produce a plaster cast of the article, and eliminating the magnetic field entirely from the space occupied by the balls after the cast has hardened thereby causing the balls to become displaceable again to permit removal of the cast without injury thereto.
26. The combination with a container, a mobile magnetizable material carried thereby and adapted to receive an impression of an article engaging it under pressure, and a magnet for thereafter rendering said material sufficiently immobile to sustain a substantial pressure.
27. The combination with a container, of mobile magnetizable material carried thereby and adapted to conform to the shape of an object engaging it under pressure, and a magnet for rendering said material sufficiently immobile to support the object under pressure after the material has conformed to the shape thereof.
28. The combination with a container and mobile magnetizable material in the container adapted to be displaced under pressure to conform to the shape of an object pressed against it, of a magnet arranged to render said material immobile after it has conformed to the shape of the object, thereby rendering said material capable of supporting said object without further displacement under further pressure.
29. The combination with a container of a plurality of loose particles of magnetizable material carried thereby and adjustable to accommodate themselves to the contour of an object under pressure, and means for magnetizing said particles to cause them to adhere to one another and thereby to resist displacement from adjusted positions.
